UNITED STATES PATENT OFFICE.

WILLIAM R. NOE, OF EAST ORANGE, NEW JERSEY.

DESIGN FOR A HANGING RECEPTACLE.

40,387.

Specification for Design.

Patented Dec. 7, 1909.

Application filed October 14, 1909. Serial No. 522,687. Term of patent 3½ years.

To all whom it may concern:

Be it known that I, WILLIAM R. NOE, a citizen of the United States, residing at East Orange, in the county of Essex and State of New Jersey, have invented a certain new, original, and ornamental Design for a Hanging Receptacle, of which the following is a specification, reference being had to the accompanying drawing, forming part thereof.

The figure is a perspective view showing my new design.

I claim:—

The ornamental design for a hanging receptacle, as shown.

WILLIAM R. NOE.
